UNITED STATES PATENT OFFICE.

ARTHUR S. DEEM, OF READING, PENNSYLVANIA, ASSIGNOR OF ONE-HALF TO ISAAC BEAR,
OF READING, PENNSYLVANIA.

INSULATOR.

No. 872,993.

Specification of Letters Patent.

Patented Dec. 3, 1907.

Application filed July 6, 1907. Serial No. 382,462.

To all whom it may concern:

Be it known that I, ARTHUR S. DEEM, a citizen of the United States, residing at Reading, in the county of Berks and State of Pennsylvania, have invented certain new and useful Improvements in Insulators, of which the following is a specification.

This invention relates to improvements in insulators for electric wires and the device is shown in the form of a cleat.

The object of the present device is to provide for taking up the "slack" in the wire.

Heretofore cleats have been made with serrated grooves the surfaces of which are substantially parallel. This construction will clamp the wire but will not take up any of the slack. In my present device I form the grooves deeper at the center than at the ends, in one of the cleat members and in the other I form corresponding or registering lugs, adapted to enter said grooves, thus taking up a portion of the slack at each cleat while still securely holding the wire.

The invention is more fully described in the following specification and clearly shown in the accompanying drawing, in which:

Figure 1 shows the meeting faces of both cleat members. Fig. 2 is a sectional view, enlarged, showing how the wire is held between the members.

The numeral 1 designates the lower cleat member. This member is formed with one or more grooves 3 to receive the wire 2. These grooves are depressed at the center, being deeper at that point than at the sides.

The numeral 4 designates the top member. This member is formed with a corresponding number of lugs 5, substantially semi-circular in outline, adapted to enter the grooves in the opposite member.

Both members are provided with the usual screw holes for securing them together and when the wire is placed in the grooves and the members drawn together, the wire is forced into the grooves and a portion of the slack is thereby taken up. When the wire is strung, and fastened at both ends, there is necessarily some slack. When a sufficient number of my cleats are applied thereto this slack is entirely taken up, each cleat taking up a small portion thereof.

The device may be made in any form and I do not desire to limit myself to the exact form shown. Circular or square posts may be formed with these grooves and lugs with equal facility.

Having thus fully described my invention, what I claim and desire to secure by Letters Patent is:

1. An insulating cleat for electric wires comprising two members, having plain meeting surfaces, one of which is provided with transverse concaved grooves spaced apart, the other member having integral convex lugs correspondingly spaced and adapted to enter said grooves, said lugs and said grooves terminating within said plain surfaces and leaving a margin on either side thereof.

2. An insulating cleat for electric wires comprising two members having registering grooves and lugs terminating short of the opposite edges of the cleat, whereby clamping shoulders are formed at opposite sides of the registering grooves.

In testimony whereof I affix my signature, in presence of two witnesses.

ARTHUR S. DEEM.
